UNITED STATES PATENT OFFICE

2,475,454

GOLF CLUB CARRIER

Robert A. Merrill, Nashville, Tenn.

Application November 10, 1945, Serial No. 627,826

3 Claims. (Cl. 280—41)

1

This invention relates to a game accessory and has particular reference to a device for transporting and storing the various implements and appurtenances essential to the game of golf.

As is well known, in playing golf in the usual manner, an assortment of golf clubs, as well as golf balls and tees, must be carried about the golf course by the player or his attendant. These items are generally carried in a "bag" of leather or the like, the entire assembly usually constituting a source of annoyance, particularly due to its weight. Heretofore, in order to facilitate transporting such golf bags, wheeled carriages have been provided on which the bags and the implements therein, are set. Such carriages are rather bulky since they are necessarily difficult to store and generally require separate handling of both the bag and the carriage.

One object of the invention is to provide a light and compact golf implement carrying device.

Another object of the present invention is to consolidate a golf bag and carriage therefor.

A further object is to provide a golf implement carrying device which may be set in upright position when not being moved about.

Another object is to provide an improved form of golf ball container and dispenser for a golf implement container.

A still further object is to provide an improved form of "clothes" compartment for a golf bag.

The manner in which the above and other objects of the invention are accomplished will be readily understood on reference to the following specification when read in conjunction with the accompanying drawings wherein:

Fig. 1 is a side view of a golf implement containing device embodying the present invention, said view illustrating the container in an upright position with the carriage locked in a transporting position.

Fig. 2 is a rear view of the device.

Fig. 3 is a side view of the device, illustrating the carriage in a storing position.

Fig. 4 is a plan view of the device.

Fig. 5 is an enlarged view, partly in section, of the telescoping member of the carriage.

Fig. 6 is a longitudinal sectional view, with parts broken away, of the container.

Fig. 7 is a side view of a modified form of the invention, illustrating the golf implement containing device in upright position and with the carriage thereof in a transporting condition.

Referring to Figs. 1 to 6, inclusive, the device comprises an elongated cylindrical golf club con-

2

tainer 11, preferably constructed of sheet metal so as to be self-supporting. The container is closed at its lower end by a bottom plate 12 which is somewhat larger in diameter than the diameter of the container whereby to form a substantial base for standing the container on end.

A carriage, generally indicated at 13, and provided for the purpose of wheeling the container about, is integrally attached to the container.

10 The carriage comprises a U-shaped frame including two tubular members 14 integrally attached to a cross member 15 forming an axle for a pair of supporting wheels 16 located on opposite sides of the container. The members 14 are pivotally attached at their upper ends to the sides of the container 11 by trunnions 20. A central telescoping tubular member is provided to locate the carriage in its different positions and comprises a lower section 17 integrally attached to the cross piece 15 and an upper section 18 pivotally attached at 19 to the upper portion of the container. The section 17 comprises a short tube 17a (Fig. 5) slidable within the section 18.

The carriage is adapted to be locked in either

25 a "transporting" position illustrated in Figs. 1 and 2 or in a "storing" position illustrated in Fig. 4. The locking device comprises a latch 21 (Fig. 5) pivoted at 22 to ears extending upwardly from the upper tubular section 18. The

30 latch is pressed in a clockwise direction by a tension spring 23 having one leg thereof secured to the section 18 and the other leg thereof underlying a tail 21a on the latch. A bolt 24 is formed on the lower end of the latch and passes through an aperture in the section 18. The bolt 24 also

35 extends, when the sections 17 and 18 are telescoped as shown in Fig. 5, through an aperture in the portion 17a of the lower section 17, thus holding the carriage 13 in its transporting position. Another aperture 25 may, if desired, be

40 provided in the upper portion of the tubular section 17a, to allow the latch bolt 24 to be inserted therein when the sections 17 and 18 are in their extended positions whereby to lock the carriage 45 in its storing position illustrated in Fig. 3.

It will be noted that when the carriage 13 is in its transporting position the lower peripheries of the wheels 16 lie tangent to a plane passing through the base 12 so that when the container is placed in an upright position illustrated in Figs. 1 and 2, the wheels and base 12 will form a 3-point support to adequately maintain the container in upright position.

It will be further noted that the lower tubular section 17 is bent at an angle whereby, when the

carriage 13 is collapsed into a storing position (Fig. 3) the frame formed by the tubular members 14 will be allowed to swing into a position wherein the wheels 16 are directly below the container so as to take up a minimum amount of space laterally. Also, in this position the tubular members will all lie closely adjacent the container 11.

A handle 26 is provided at the top of the container to aid in handling the latter and is mounted on links 27 pivotally attached at 28 to the sides of the container.

In the lower portion of the container 11 there is integrally attached to the container wall a semi-circular plate 126 having the free edge thereof covered with a soft bumper 127. The plate is provided to support the handles of the shorter golf clubs.

Integrally attached to a rim 128 at the top of the container are a pair of spaced transversely extending separating rods 129 provided to space the golf clubs into different groups.

The interior of the container 11 is preferably covered with fabric cloth 130 or the like to prevent wear and noise.

A golf ball container is integrally attached to the wall of the main container 11 and comprises a tube 29 (Fig. 6) wherein golf balls indicated by dotted lines 30 may be stored, one on top of each other. The tube is closed at its lower end and open at its upper end. The latter has a freely slideable shelf 31 on which the balls 30 rest. A tab 32 extending from the shelf 31 passes through a longitudinally extending slot 33 in the tube whereby the shelf may be raised to eject the golf balls, one at a time, from the top of the tube.

A pair of tubes 34 are integrally attached to opposite sides of the ball tube 29 for storing tees or the like. At the bottom of each of these tubes is provided a hole 29a through which a pencil or the like may be inserted to eject the tees from the top.

A cover 35 extends coextensively over the tubes 29 and 34 and is pivoted at 36 to the container 11 whereby it may be swung upwardly to allow access to the different tubes. A wire spring clip 35a is provided to frictionally engage the interior of the golf tube and thus hold the cover in position when covering the tubes.

Means are provided for storing clothes, etc. and comprises a box-like container 37 having a front wall 38, rearwardly extending side walls 39, a bottom wall 40 and a top wall 40a. The container 37 is guided toward and away from the main container 11 by side plates 41 secured to the wall of the container 11. That is, the sides 39 of the container 37 are guided by the close fitting plates 41.

Springs 42, located in each of the corners of the container 37, are tensioned between the front wall of the container and the wall of the container 11 to normally hold the container 37 in intimate contact with the container 11 as illustrated. However, the springs permit the clothes container to be pulled outwardly, as by a handle 43, to allow clothes or the like to be inserted therein. The container 37 is limited in outward movement at its lower end by a pin and slot arrangement comprising pins 44 extending laterally from the sides 39 of container 37 and movable along laterally extending slots 45 in the guide plates 41.

For the purpose of preventing unauthorized opening of the clothes container, an angle piece 46 is mounted at the top of the container in juxtaposition with an angle piece 47 extending from the wall of the main container 11. Coextensive openings are formed in the pieces 46 and 47 through which a padlock may be inserted.

Fig. 7 illustrates a modified form of the invention in which a golf club carrier, generally indicated at 50, is substituted for the cylindrical container 11. The container comprises a tubular stand 51, to the bottom of which is integrally attached a base plate 52 whereby the container may be stood upright in its illustrated position.

A pair of circular plates 53 and 54 are secured to the stand 51 adjacent the top and bottom thereof, respectively. These plates have a series of aligned openings 55 therein through which the handles of golf clubs, as indicated by the dot and dash lines 56, may be inserted.

The tubular stand 51 may be utilized to contain a series of golf balls in the same manner as the tube 29 (Fig. 6), and for this purpose a longitudinally movable shelf 31a is fitted within the stand, the shelf being provided with a tab 32a movable along a longitudinally extending slot (not shown) whereby the shelf may be raised to eject balls from the top of the stand.

A carriage generally indicated at 13a and similar to the carriage 13 of Figs. 1 to 6, is provided to wheel the stand and to also form a 3-point support therefor when it is stood upright, it being noted that the bottoms of the peripheries of the wheels 16a lie tangent to a plane passing through the base plate 52.

Having thus described the invention what I claim as new and desire to obtain by United States Letters Patent is:

1. In a device of the character described, an elongated container, a frame, a pair of coaxially extending supporting wheels for said frame, means pivotally supporting said container intermediate its ends on said frame, an extensible member having one section thereof connected to said frame and another section thereof pivotally connected to said container above said first mentioned means, and means for selectively locking said member against extension whereby to maintain said container in transporting position and for permitting said sections to extend relative to each other whereby to permit said container to be located in storing position.

2. In a device of the character described, a carrier, a frame, a pair of coaxially extending supporting wheels for said frame, coaxially extending supporting wheels rotatably mounted at one end of said frame, means pivotally connecting said frame adjacent the opposite end thereof to said carrier above the bottom thereof, the relationship of the position of said pivotal connection to said frame being such that said frame may be swung from a position wherein said wheels are located to one side of said carrier in a transporting position to a position wherein said wheels are located below and adjacent the bottom of said carrier in a storing position, an extendable device connecting said frame and said carrier, said device comprising a lock effective to lock said frame in said transporting position, and said device being arranged to extend adjacent said container when said frame is in said storing position.

3. In a device of the character described, a carrier, a frame, a pair of coaxially extending supporting wheels for said frame, coaxially extending supporting wheels rotatably mounted at one end of said frame, means pivotally connecting said frame adjacent the opposite end thereof to said carrier above the bottom thereof, the relation-

tionship of the position of said pivotal connection to said frame being such that said frame may be swung from a position wherein said wheels are located to one side of said carrier in a transporting position to a position wherein said wheels are located below and adjacent the bottom of said carrier in a storing position, an extendable device connecting said frame and said carrier, said device comprising a lock effective to lock said frame in either of said positions, and said device being arranged to extend adjacent said container when said frame is in said storing position.
